(57) **CLAIM**

The ornamental design for a table, as shown and described.

DESCRIPTION

FIG. 1 is a top perspective view of the table;

FIG. 2 is a bottom perspective view of the table shown in FIG. 1;

FIG. 3 is a top plan view of the table shown in FIG. 1;

FIG. 4 is a bottom plan view of the table shown in FIG. 1;

FIG. 5 is a front elevational view of the table shown in FIG. 1;

FIG. 6 is a rear elevational view of the table shown in FIG. 1;

FIG. 7 is a right side elevational view of the table shown in FIG. 1; and,

FIG. 8 is a left side elevational view of the table shown in FIG. 1.

In the drawings, the broken lines show portions of the table that form no part of the claimed design.
